UNITED STATES PATENT OFFICE.

FREDERICK JAMES SIMPSON GILBERT, OF NEW ORLEANS, LOUISIANA.

PRINTING-FRAME.

SPECIFICATION forming part of Letters Patent No. 712,295, dated October 28, 1902.

Application filed June 14, 1902. Serial No. 111,714. (No model.)

To all whom it may concern:

Be it known that I, FREDERICK JAMES SIMPSON GILBERT, a subject of the King of Great Britain, and a resident of New Orleans, in the 5 parish of Orleans and State of Louisiana, have invented a new and Improved Printing-Frame, of which the following is a full, clear, and exact description.

My invention relates to printing-frames of 10 the kind used in photography and the arts allied thereto.

Reference is to be had to the accompanying drawings, forming a part of this specification, in which similar characters of reference indicate corresponding parts in both the figures.

Figure 1 is a plan view, partly in section, showing my invention as applied to an ordinary photographic-printing frame, and Fig. 2 is an enlarged section upon the line 2 2 of 20 Fig. 1 looking in the direction of the arrows and showing the film and sensitive paper in place.

A wooden rectangular frame consisting of the members 1 2 3 4 is provided with a window 5 or glass plate 5 and with clamp-holes 6 7. A removable back 8 fits into this frame in the usual manner. Upon the glass plate or window 5 a film 9 is placed, and upon this film, parallel with and adjacent to two of the 30 edges thereof, are longitudinal wires 10. One end of each wire is wrapped upon a revolvable pin 11, which is provided with a milled head 12 for the purpose of being engaged by the finger. The member 1 is provided with apertures 13, in which the coils of the wires 10 are wound. The other end of each wire is provided with a knot 14, which engages the aperture 15 in the member 3 of the frame. A sheet of sensitive paper 16 is placed over the 40 film, one edge of this sensitive paper overlapping the wire 10.

It should be remembered that the films ordinarily used in photography are generally stiff and liable to curl and twist, sometimes 45 without any apparent cause. In the ordinary printing-frame when the film is placed upon the window or glass plate and the sensitive paper is in turn placed upon the film it is frequently desirable to remove the back plate 50 of the frame and look at the edge of the sensitive paper. In doing this the film tends to

curl and the photographer frequently has difficulty in forcing the edge of the film back to its normal position. With my device, however, these difficulties are overcome. I merely 55 loosen the revolvable pins 11 by means of the milled heads 12, thereby slackening the wires 10 to a slight degree. I next insert the film into the frame, so that two opposite edges are engaged by the wires 10, and then tighten the 60 wires by means of the pins 11 and heads 12. I next place the sensitive paper over the film, and consequently let two of the edges of the sensitive paper slightly overlap the wires. This slight overlapping does not affect the 65 printing of the image upon the sensitive paper for the reason that a little margin is always allowed—that is to say, a space immediately adjacent to the border of the sensitive paper is not used for printing, and a 70 space immediately adjacent to the border of the film or negative is not used for the purpose. If now the back plate 8 be placed in position, the printing may be proceeded with in the usual manner, and the edges of the 75 sensitive paper may be examined at intervals by the photographer without any danger of the film giving trouble of the kind above described. It is simply held down at the two opposite edges by the wires 10, as above explained.

Having thus described my invention, I claim as new and desire to secure by Letters Patent—

1. A printing-frame, comprising a hollow 85 casing provided with a window for receiving the film to be copied, and with a longitudinal extensible member for engaging said film adjacent to one of the edges thereof, and a removable back for securing sensitive paper 90 upon said film and said longitudinal member.

2. A printing-frame, comprising a hollow casing provided with a window for receiving a film to be copied, and also provided with a longitudinal flexible member for engaging 95 one of the edges of said film, said flexible member being free to hold said edge of said film against said window, and a removable back for holding sensitive paper against said film and said longitudinal flexible member. 100

3. A printing-frame, comprising a hollow casing provided with a window for receiv-

ing a film to be copied, a longitudinal wire stretched across said casing internally, and free to engage said film adjacent to one of the edges thereof, and a removable back for holding sensitive paper upon said film and said wire.

4. A printing-frame comprising a hollow frame provided with a window for receiving the film to be copied, a removable back, and 10 a film-clamping member attached to said frame and arranged to hold the film in place on the removal of the back from the frame.

5. A printing-frame, comprising a hollow casing provided with a window for receiving 15 a film to be copied, a longitudinal wire stretched across said casing internally, and free to engage said film adjacent to one of the edges thereof, means controllable at will for tensioning said wire, and a removable back

for holding sensitive paper upon said film and 20 said wire.

6. A printing-frame, comprising a hollow casing provided with a window for receiving a film to be copied, a longitudinal wire stretched across said casing internally and 25 free to engage said film adjacent to one of the edges thereof, an adjustable friction device for tensioning said wire, and a removable back for holding sensitive paper upon said film and said wire.

In testimony whereof I have signed my name to this specification in the presence of 30 two subscribing witnesses.

FREDERICK JAMES SIMPSON GILBERT.
